FLOWER POT BASE

Frederick A. Burke, Riverside, Conn., Joel A. Farrell, Carlisle, Mass., and Douglas A. Long, Wilton, Conn., assignors to The Gillette Company, Boston, Mass.

Filed Aug. 13, 1975, Ser. No. 604,104

Term of patent 14 years

Int. Cl. D11—02

U.S. Cl. D35—3 A

Fig. 1

Fig. 2

Fig. 3

Fig. 4

FIG. 1 is a perspective view of a flower pot base showing our new design;

FIG. 2 is a side elevational view thereof, all four sides being substantially the same;

FIG. 3 is a top plan view thereof; and

FIG. 4 is a bottom plan view thereof.

We claim:

The ornamental design for a flower pot base, substantially as shown.
